UNITED STATES PATENT OFFICE.

FRED L. MACKENZIE, OF BEVERLY, MASSACHUSETTS, ASSIGNEE TO UNITED SHOE MACHINE CORPORATION, OF PATERSON, NEW JERSEY, A CORPORATION OF NEW YORK.

METHOD OF MAKING SHOES AND INNERSOLE THEREFOR.

Application filed September 9, 1921. Serial No. 499,459.

This invention relates to methods of making shoes and to innersoles for shoes, particularly shoes of the stitchdown type, that is, shoes in which the margin of the shoe 5 upper is turned outwardly and secured to the margin of the sole.

In a usual method of making stitchdown shoes a flat sole or innersole is attached to a last, the margin of the sole projecting beyond the edge of the last a suitable distance. An upper is placed over the last and properly located thereon. The upper is then lasted into the angle between the side of the last and the projecting margin of the sole 15 and fastened in the angle. If the sole applied to the last is an innersole, an outersole is next applied to the attached innersole and a welt strip to the face of the outward margin of the upper, and the welt, 20 upper, innersole and outersole are sewed together. This method, while extensively used and well adapted for the manufacture of certain grades of shoes, produces a shoe which, for some uses, is objectionable in certain respects. For example, the welt, since it 25 is above the plane of the inner face of the innersole, reduces the apparent height of the toe and produces an obstruction to outward bending of the upper near the sole which 30 may cause discomfort to the wearer. Furthermore, shoes made by the prior method above described are cold for winter wear since there is no layer of insulating material between the soles, such as is afforded by 35 the cork filling of a welt shoe, to protect the foot from the cold ground.

In view of these considerations, objects of the present invention are to provide a method of making stitchdown shoes by the practice of which a shoe will be produced in which the top face of the welt is substantially in the plane of the inner face of the portion of the innersole inside the shoe and in which a filling will be provided between 40 the inner and outer soles which will not add to the thickness of the shoe edge.

In carrying out the novel method of the present invention, as herein illustratively exemplified, an innersole of substantially uniform thickness is first formed or molded 45 with the marginal portion offset from the body portion which engages the bottom of the last in such manner that the marginal

portion, while still in a plane parallel to the bottom of the innersole or last, is displaced, in a direction perpendicular to the last bottom, a distance substantially equal, for example, to the thickness of the inner sole or at least a distance equal to the thickness of the welt and upper, so that 55 the upper or inner face of the margin of the innersole is substantially in the plane of the outer face of the body of the innersole, the result being that, in the completed shoe, the exposed face of the welt strip is substantially in the plane of the inner face of the body of the innersole. This offsetting of the margin of the innersole has the further advantage that it forms on the bottom of the innersole a recess inside the margin of the 60 innersole in which a filler may be inserted to afford between the inner and outer soles beneath the foot additional insulation and additional thickness of the sole material between the foot and the ground. The innersole thus formed is attached to the bottom of a last and an upper, the end portions of which have preferably been molded substantially to the shape which they are to assume 65 in the finished shoe, assembled thereon. The upper is then lasted against the offset portion of the innersole and secured thereto. The filling of the innersole, the laying of the outsole, the application of a welt to the flange of the upper and the attachment of 70 the welt, upper, innersole and outsole together are carried out in the usual manner.

In another aspect the invention comprises an innersole as a separate article of manufacture, said innersole, before attachment to the other parts of the shoe, being formed from material of uniform thickness with an imperforate margin offset with respect to the body of the innersole a distance substantially equal to the thickness of 75 the innersole and parallel thereto.

In the drawings,

Fig. 1 is a perspective view, partly broken away, of an innersole prepared in accordance with the present invention;

Fig. 2 is a view showing the use of a stapling machine for securing the upper to the innersole;

Fig. 3 is a view illustrating the use of 105 sewing mechanism for securing the upper and innersole together;

Fig. 4 is a detail in section and perspective showing the upper attached to the innersole by stitches;

Fig. 5 is a sectional view of the shoe upon a last during the operation of attaching the outsole and welt; and

Fig. 6 is a perspective view of the completed shoe, parts being in section and broken away to show the construction.

- 10 In the practice of the method of the present invention an innersole is first prepared as shown in Fig. 1 with a body portion 2 substantially of the size and shape of the bottom of a last to be used and with the 15 marginal portion 4 offset from the body portion, the amount of offset as indicated at 6 being preferably at least as much as the combined thickness of the upper and welt. The operation of offsetting the margin 4 of the sole may be effected by suitable molds or may be performed progressively by the use of rolls. The innersole thus prepared is secured to the bottom of the last 8 with the body portion covering the last bottom and the offset margin spaced perpendicularly from the last bottom but substantially in a plane parallel to it. An upper 10, the toe and heel portions of which are preferably molded to substantially their final shape, is then placed over the last and is lasted and secured to the innersole either as shown in Fig. 2, by the use of a staple lasting machine such as that disclosed in United States Letters Patent 35 No. 1,291,754 granted January 21, 1921 on application of Matthias Brock, or by a sewing machine as illustrated in Fig. 3. Various kinds of sewing mechanisms may be found suitable, or easily adapted, for this 40 work, for example, a chain-stitch sewing machine such as a turn shoe machine may be employed, the chain of the stitch being preferably formed at 11 on the inner side of the offset 6 as shown in Fig. 4. If desired, the stapling machine may be employed to secure the upper to the innersole at a number of relatively widely spaced points about the periphery of the shoe, this operation corresponding to the usual pulling-over operation by which the upper is 50 properly located on the last and secured to the innersole under tension. The turn shoe machine or other sewing instrumentalities may then be employed as indicated in Fig. 53 to unite the upper and the offset portion of the innersole about the periphery of the shoe. The fastenings in either case are preferably inserted through the offset 6, that is, through the portion connecting the 55 body portion with the offset portion 4. In Fig. 3 the channel guide of the sewing machine is indicated at 20, the curved awl at 22 and the curved needle at 24. A rest 26 is provided to engage the offset and support it during retraction of the needle, the

rest being arranged to withdraw from the work during the feed of the work. This rest is similar in action to the usual edge rest with which machines of this type are provided but is shaped to engage the offset 70 of this type of shoe instead of the edge of the shoe as it is when the machine is employed for sewing the usual inseam.

It is to be understood, of course, that at the heel-seat portion of the innersole the 75 offset formation may be omitted together with the extension of the innersole beyond the edge of the last, and that the upper may be lasted inwardly as is a usual practice.

After the upper has been lasted and secured to the innersole the tacks or other means holding the innersole to the last are removed and the cavity of the innersole inside the offset 6 is filled with a suitable 80 filler 12, for example, felt or the usual cork composition. An outsole 14 is then laid over the filler and the margin 4 of the innersole to which it may be secured by cement or otherwise. The shoe is now ready for the attachment of the outsole which operation 85 may be performed in any known manner, for example, by the use of an outsole stitching machine. During this operation a welt 16 is preferably placed over the exposed 90 surface of the outturned flange of the upper 95 and sewed by a seam 18 to the upper, innersole and outsole, as indicated in Fig. 5.

Having described my invention, what I claim as new and desire to secure by Letters Patent of the United States is:

1. That improvement in methods of making stitchdown shoes which consists in providing an innersole of uniform thickness, shaping the innersole with an offset spaced from its edge, lasting the upper against the offset on the outside and securing the upper by fastenings passing through the offset, and attaching an outsole to the margin of the innersole and upper.

2. That improvement in methods of making stitchdown shoes which consists in providing an innersole of uniform thickness, shaping the innersole with an offset uniformly spaced from its edge, the margin being in a plane parallel to the body portion, lasting the upper against the offset on the outside, securing the upper by fastenings passing through the offset, filling the sole inside the offset portion, and attaching an outsole to the margin of the innersole and upper.

3. That improvement in methods of making stitchdown shoes which consists first in offsetting the marginal portion of an innersole, then securing the upper to the innersole between the body of the sole and the offset margin, and finally securing an outsole to the outer face of the margin and a welt to the flange of upper covering the margin.

4. That improvement in methods of mak-

100

105

110

ing stitchdown shoes which consists in forming an offset marginal portion on an inner-
sole, such that the margin is displaced from
the plane of the last bottom a distance equal
5 at least to the thickness of upper and welt,
securing the upper to the innersole between
the body of the sole and the offset margin,
and then securing an outsole to the outer
face of the margin and a welt to the flange of
10 upper covering the margin.

5. That improvement in methods of mak-
ing stitchdown shoes which consists in pro-
viding a relatively thin innersole of uniform
thickness, offsetting the marginal portion of
15 the innersole, securing the upper to the in-
nersole between the body of the sole and the
offset margin, filling the recess in the outer
face of the innersole formed by offsetting the
margin, and then securing an outsole to the
20 outer face of the margin and filler and welt
to the flange of upper covering the margin.

6. That improvement in methods of mak-
ing stitchdown shoes which consists in mold-
ing an innersole to position a surface of the
25 marginal portion parallel to and substantial-
ly in the plane of the opposite face of the
body portion, placing the innersole upon a
last with the marginal portion spaced out-
wardly from the plane of the last bottom,
30 molding the toe and heel portions of an
upper, placing the molded upper upon the
last, securing the upper in outturned posi-
tion to the innersole along the inner line of
the margin, applying an outer sole and se-
35 curing the upper, innersole and outersole to-
gether.

7. That improvement in methods of mak-

ing stitchdown shoes which consists in mold-
ing an innersole to position a surface of the
marginal portion substantially in the plane 40
of the opposite face of the body portion,
placing the innersole upon a last with the
marginal portion spaced outwardly from
the plane of the last bottom, placing an up-
45 per upon the last, lasting and securing the
upper in outturned position to the innersole
along the inner line of the margin, filling the
innersole, placing a welt on the outturned
margin and an outersole on the outer face 50
of the filler and margin, and sewing the
welt, upper, innersole and outersole together.

8. An article of manufacture consisting of
an unattached innersole of uniform thickness
and having a body portion and an imper-
forate marginal portion extending outward- 55
ly from the body portion parallel thereto
and offset perpendicularly to the plane of
the body portion a distance substantially
equal to the thickness of the innersole.

9. A separate article of manufacture, con- 60
sisting in an unattached innersole for stitch-
down shoes, said innersole being of uniform
thickness and having the marginal portion
which is to extend beyond the last bottom im-
perforate and offset with respect to the por- 65
tion which is to cover the last bottom, the
amount of said offset being substantially
equal to the thickness of the innersole and
said margin remaining parallel to the re-
mainder of the innersole. 70

In testimony whereof I have signed my
name to this specification.

FRED L. MACKENZIE.
